UNITED STATES PATENT OFFICE.

FRANK ELLIS KABASE, OF BIRMINGHAM, ALABAMA.

FURNACE FOR BURNING COKE AND CHARCOAL.

1,236,573.

Specification of Letters Patent. Patented Aug. 14, 1917.

Application filed September 28, 1916. Serial No. 122,664.

To all whom it may concern:

Be it known that I, FRANK ELLIS KABASE, a citizen of the United States of America, residing at Birmingham, in the county of 5 Jefferson and State of Alabama, have invented certain new and useful Improvements in Furnaces for Burning Coke and Charcoal, of which the following is a specification.

10 My invention relates to furnaces of the type generally known as charcoal burning heating furnaces for irons, cooking utensils and the like, and my object is to design the furnace that coke may be substituted for 15 charcoal and burned with equal effectiveness, thus making possible the use of a less expensive and more plentiful fuel, and, as a result, increasing the range of usefulness of the furnace.

20 My invention consists of a metallic casting or jacket having a removable clay tile lining, the jacket carrying movable supporting members at its upper end adapted to be swung inwardly to overhang the opening in 25 the tile lining and also adapted when swung outwardly to receive between their supporting loops an extension casing which may serve as a flue or a heating drum, or the like.

20 My invention comprises the foregoing 30 novel features and other details of construction which are hereinafter more particularly described, reference being had to the accompanying drawings, in which:—

Figure 1 shows my furnace in plan; and 35 Fig. 2 shows it in side elevation partly broken away.

Fig. 3 shows the furnace with the blower stack mounted thereon and the hinge support swung out; and

40 Fig. 4 illustrates the furnace with a heating drum mounted thereon.

Similar reference numerals refer to similar parts throughout the drawings.

As illustrated, my furnace comprises a 45 cylindrical metallic casing 1, a bottom 2 and supporting legs 3 which are attached preferably to the lower part of the casing. Customary brackets 4 for the handle 5 are also attached to the casing. Within the casing 50 is inserted a removable tile or heat insulating sleeve 6 formed of refractory material, which tile or sleeve may be burnt if desired to toughen it for shipment. This tile is molded or formed with its inner bore 55 slightly tapering toward the base and within

it is inserted a removable grate 7, having supporting legs 8 attached to or formed integral therewith and of such length as to positively support the grate above the bottom of the casing coincidentally with its 60 reaching a point in the taper bore of the sleeve where it makes a tight fit. In such position it stands above the side opening 9 for the admission of air and the withdrawal of ashes. This opening 9 extends through 65 the metallic casing and through the tile. A slide door 10 is provided for the opening 9 and travels in vertical guides 11 attached to the outer wall of the casing 1. Three hinge straps 12 are shown attached at the 70 top of the metallic casing with their hinge loops exposed above the top of the casing and there adapted to receive the inturned ends of a wire bail 13, which bails project beyond the lining 6 and overhang the furnace proper. I prefer three of these, but 75 obviously more or less may be used and they project sufficiently inwardly to support on their free ends a pot, a pan or the customary irons.

It will be obvious that these bails may be swung back so as to clear the top of the casing and when such is the case I may mount thereon a bottom cone 14 of a blower or draft stack 15 having therein a damper 16 for purposes of control and which is suitable for producing the necessary draft for rapidly igniting the coke when such is used. In the event it is desired to use the furnace for room heating purposes, a radiating drum 17 is provided which is adapted to be mounted on the top of the vessel 1 and which is provided with a closed top 18, handles 19 and outlet ports 20 for the products of combustion. A vertically movable slide door 21 90 is provided thereon to close a side opening through which fuel may be introduced or the fire poked. Legs 23 on the heating drum 95 will fit about the casing 1 and hold the heater more securely thereon.

100 What I claim as new and desire to secure by Letters Patent, is:—

1. A heating furnace of the character described, comprising a refractory lined metal casing, and bail shaped loops hinged to the 105 upper end of the casing and adapted to fold over and rest on the casing with their free ends projecting over the furnace proper, said loops being adapted to fold outwardly and downwardly against the casing, in com- 110

bination with a furnace attachment adapted to seat on top of the casing to form a continuation thereof.

2. A heating furnace of the character described, comprising a cylindrical casing lined with refractory material and having a bottom air inlet port and an open top, of hinge straps attached outside to the top of the casing and arranged to project substantially above the same, supporting members hinged to the straps and adapted to fold outwardly against the casing and inwardly onto the furnace top into position to overhang the furnace, and a furnace attachment adapted to seat on the furnace casing top and be held by said hinge straps against lateral displacement when said supporting members are swung outwardly.

3. A heating furnace of the character de-

scribed, comprising a metallic, refractory lined casing, bent metal hinge straps which are connected to the top of the casing and each having a hinge loop projecting above the top of the casing in position to receive and center thereon a top extension member, 25 a top extension member, and supporting members for articles to be heated formed by loops of wire with the ends of each supporting member inturned and sprung into the hinge loop of a strap and adapted to 30 rest on the casing top when in horizontal inturned position and adapted to fold outwardly against the casing side.

In testimony whereof I affix my signature.

FRANK ELLIS KABASE.
